ABSTRACT

A frame of individual rectangular elements meeting at their corners to form opening mounts rectangular panels by means of bolts held in the openings and having at their heads spring members that enter, and releasably lock in, recesses provided in the corners of each panel.

COMPOSITE PANEL ARRANGEMENT

BACKGROUND OF THE INVENTION

The invention relates to a composite panel structure comprising polygonal panels fastened to a frame of which the frame elements have meeting corner portions.

The composite panel structure is particularly intended to be used in monitoring and control stations to monitor and control industrial processes or the power grid of a city, for example. The mosaic "stones," which are injection molded of a suitable synthetic plastic material, and are usually 25 to 50 mm. square, or else 25×50 mm., in size, have on their exposed surface the symbol of the element they represent. A complete panel therefore shows schematically an entire manufacturing process, for example, and composes a kind of mosaic circuit diagram. Moreover, switching units and indicators, such as control lamps and current and voltmeters, can be mounted in the panels to be visible to the personnel, who thereby can monitor and control that which is schematically represented on the panel.

In the prior art there are described several solutions to the problem of fixing rectangular mosaic stones to the frame of a mosaic circuit diagram. The underside of the stones have four milled grooves, Z-shaped in cross section and concentric to a respective corner edge. These solutions employ two springs and two round guide bolts at diagonally opposite corners of a frame unit, the springs locking into the aforementioned grooves. Two guide bolts engage the lower edge of the corresponding groove and prevent the mosaic stone from turning.

This anchoring arrangement has the disadvantage that the mosaic stones are rather loosely held on the mounting frame, because they are held at only two diagonally opposite corners and positioned by only two diagonally opposite guide bolts. Particularly loosely held are those mosaic stones located along the edge, since the springs at the edge are only slightly tensioned.

A further disadvantage is that the grooves extend arcuately, so that the cost of manufacture of the mosaic stone is increased.

SUMMARY OF THE INVENTION

An object of the invention is to produce a composite panel structure of which the mosaic stones are held and positioned at each of their corners.

Another object of the invention is a composite panel structure of which the arrangement for anchoring the mosaic stones is relatively simple in construction and inexpensive to manufacture.

A still further object of the invention is a composite panel structure for monitoring and control stations and of which the mosaic stones are held and positioned at each of their corners.

Broadly, the invention embraces a composite panel structure comprising a latticelike frame including a plurality of frame elements having meeting corner portions, a plurality of polygonal, usually square, panels adjacent to one side of the frame and having corner portions overlying the corner portions of adjacent frame elements, the corner portions of the panels having recesses that extend substantially diagonally inwardly from the respective corner portions and each having a wider portion and a narrower portion disposed between the respective wider portion and the one side of the frame, and coupling means separably securing the panels to the frame, including substantially annular elastic retaining members mounted at the meeting corner portions of the frame elements and received in the wider portions of the adjacent recesses, the panels being separable from the frame in response to deformation of the retaining members during passage through the narrower portions of the respective recesses.

The novel features which are considered as characteristic for the invention are set forth in particular in the appended claims. The invention itself, however, both as to its construction and its method of operation, together with additional objects and advantages thereof, will be best understood from the

following description of specific embodiments when read in connection with the accompanying drawing.

BRIEF DESCRIPTION OF THE DRAWINGS

- 5 FIG. 1 is a plan view of the mosaic circuit diagram of the invention, with some of the mosaic stones removed;
 FIG. 2 is a detail on expanded scale of FIG. 1.
 FIG. 3 is a view in cross section taken along line III—III of FIG. 2;
 FIG. 4 is a view, corresponding to FIG. 3, of a third embodiment;
 FIG. 5 is a top view of the third embodiment, with the mosaic stones removed;
 FIGS. 6 and 7 are views, respectively corresponding to FIGS. 4 and 5, of a fourth embodiment;
 FIG. 8 is a top view of a fifth embodiment, with the mosaic stones removed;
 FIG. 9 is a view in section taken along line IX—IX of FIG. 8, 20 with the stones in place;
 FIGS. 10 and 11 are views, corresponding respectively to FIGS. 8 and 9, of a sixth embodiment.

DESCRIPTION OF THE PREFERRED EMBODIMENTS

- 25 FIG. 1 is a plan view of a composite, mosaic, panel structure having a mounting frame 1 composed of individual rectangular units 2 to form the latticelike frame. These units are formed by rectangular frame elements 3, which are placed together so that their corner portions meet; and a design is formed like that of the squares on a chess board. The corners of the units 2 are adjacent the axes 4, which extend perpendicular to the plane defined by the mounting frame 1. Only two frame elements 3 are adjacent each axis 4. Each element 30 consists of four sidewalls 30 rigidly connected together. These walls are also perpendicular to the plane of the frame 1. The two elements 3 adjacent an axis 4 are securely held together by a screw or bolt 5 and a nut 6, as shown in FIGS. 2 and 3. Each corner of a frame element 3 incorporates a concave 35 cavity 7 next to the axis 4. From one end of each cavity 7 projects a curved tongue 8 that partly surrounds the neighboring axis 4. As shown in the structure of FIGS. 1 and 2, the tongues 8 project between the axis 4 and the concavity 7 of the diagonally opposite frame element 3, so that the tongues of 40 two frame elements form a socket, or an opening 9 for a bolt 5. Between the cavity 7 and the surface of the neighboring tongue 8, on the one hand, and between the diameter of the bolt 5 and that of the opening 9, on the other, sufficient 45 tolerance is provided to permit adjustment for imprecise dimensions of the frame elements 3 and/or of the mosaic stones 18. FIG. 1 shows that diagonally opposite tongues 8 of an element 3 are precisely symmetrical about the center of the element. Two cooperating tongues of diagonally opposite elements 3 are point symmetrical about their common axis 4.

The tongues 8 surround the axes 4 through an arc of nearly 180°. The concave cavity 7 and the corresponding tongue 8, of the same element 3, together surround the adjacent axis 4 through an arc of approximately 270°. When a bolt 5 is placed 50 into the opening 9, the two tongues 8 of that opening surround the latter in such a manner that the two frame elements 3 thus connected together cannot be separated, irrespective of whether the nut 6 is threaded onto the bolt and tightened down. As a consequence, the frame 1 cannot collapse if the bolts 5 loosen. Each bolt, or male coupling elements, has a head 10, and a threaded shaft 11 with a nut, or female coupling element 6. The latter preferably extends beyond the length of the shaft 11, so that switching or indicating units can be mounted in the exposed part of the threaded bore of the nut. The underside of the bolt head 10 had an annular knife edge 12, concentric to the axis 4, and which is forced into the two tongues 8 underneath. Between the nut 6 and the tongue 8 is arranged a ring, or annular disc 13, which has an annular knife edge 14 that is symmetrical to the knife edge 12 to a plane passing midway between these two knife edges. The

knife edge 14 is forced from below into the two tongues 8 positioned above. In plan view the bolt head 10 is a square, as shown in FIG. 2. Each sidewall 15 of the bolt head extends parallel to the lower edge 16 of the recess 17 in a respective one of the four adjacent mosaic stones 18 meeting at their corners that coincide with the respective axis 4. The end walls of the recesses 17 are S-shaped in cross section, as can be seen in FIG. 3, which shows the end walls of two contiguous recesses. The lower edge 16 of a recess contacts the opposite sidewall 15, which positions the edge 16, so that the bolt head 10 serves as a guide means. Since each mosaic stone has at each corner a recess 17 of which the end wall makes an angle of 45° with the adjacent sides of the mosaic stone, and since at each corner of a unit 2 there is provided a bolt 5 with sidewalls 15, each mosaic stone 18 is held in position at each of its four corners by a respective sidewall 15.

The S-shaped end wall of each recess 17, and thus the edge 16, are rectilinear, as a consequence of which the milling of the recess 17 is simplified. Since the recess is straight, the diameter of the milling cutter is unimportant.

The S-shaped end wall of a recess forms a wedge-shaped surface 220 near the bottom of the recess, so that the mosaic stone presses relatively lightly on the spring 21.

The head 10 of the bolt 5 is elongated by a projection 19 that terminates in a short pin 20. The latter centers the spring 21, which is mounted on the projection and connected thereto in any suitable and known manner. The spring 21 consists of a dish-shaped, curved piece of spring steel and acts resiliently in directions extending radially from the corresponding axis 4.

In accordance with another embodiment, the spring 21 can be an annular, elastic, solid body of any suitable material, such as an elastomer.

A mosaic stone 18 is secured to a unit 2 by placing the stone over the unit, with the four corner recesses 17 of the stone in registry with the corresponding springs 21; whereupon the stone 18 is pressed against the frame 1, causing the respective wedge-shaped surface 220 to compress the spring 21 until the latter is pushed behind the edge 16 and is releasably locked in the recess 17. When locked, the spring 21, as shown in FIG. 3, presses against the inclined end wall surface 22 of the recess 17. The mosaic stone 18 is removed simply by pulling on it, so that the end wall surface 22 compresses the spring 21 until the latter has been pulled free of the edge 16.

FIGS. 4 to 7 show third and fourth embodiments, wherein the same or equivalent parts are denoted by the same reference numerals and will not be further described.

In the embodiment shown in FIGS. 4 and 5, the bent, dish-shaped spring 21 is replaced by an annular spring 121. The bolt head 110 incorporates a peripheral groove 23 in which the spring 121 is held. The opening 24 in the spring 121 is positioned opposite one of the corners of the rectangular bolt head 110, so that a respective portion of the spring projects, and acts radially, beyond each sidewall 15.

In the fourth embodiment, shown in FIGS. 6 and 7, the peripheral groove 23 is wider. The spring 221, an elastomeric annulus, round in cross section, is held in this groove and projects approximately one-half of its cross section beyond the middle of a sidewall 15 of the bolt head 210. As a consequence, the spring 221 forms a radially acting spring in the neighborhood of the sidewalls 15.

FIGS. 8 and 9, which illustrate the fifth embodiment, show two frame elements 3 with their sidewalls 30, of which latter a respective corner of each element meets the corner of the other element at the axis 4, which is perpendicular to the plane defined by the mounting frame 1. These two frame elements 3 are connected together by a bolt 5 and a nut 6. The mosaic stones 18 are releasably held to the frame 1 constructed of the individual elements 3. The bolt head 310, having the positioning, or guide, walls 15 for the edge 16 of the recess 17, is constructed as a guide means. On the bolt head 310 is held a radially acting, cup-shaped, spring member 321 that rests with its bottom 25 on the bolt head 310. The spring 321 is preferably made of synthetic plastic material. The bot-

tom 25 incorporates a centering hole 26, through which projects a centering pin 27 that is integral with the bolt head 310 and extends along the central axis of the latter. A quick lock spring 28 is pushed down over the centering pin 27 to hold the spring 321 in place.

The bolt head 310 comprises, near the knife edges of the sidewalls 15, four projections, or posts, 29 that extend parallel to the axis 4 and extend the sidewalls 15 to above the spring 321. The radially resilient wall of the spring 321 projects out from between the posts 29. Between these posts the outer surface of the spring wall has more or less semicylindrical bulges 31 that releasably lock with the S-shaped end walls of the recesses 17. The resilience of the spring is improved by four slots 32, parallel to the axis 4, provided in the spring wall in the region of the posts 29. By positioning these slots behind the posts there is gained the advantage that the radially resilient wall cannot be pressed outwards or downwards when the mosaic stone 18 is set in place.

In the last embodiment, shown in FIGS. 10 and 11, the wall of the spring 421 is beaded along its portions between the posts 29, thereby eliminating the bulges 31 of the previous embodiment. The bottom 125 of the spring is constructed as quick lock spring, making unnecessary any additional member for holding the spring 421 onto the guiding bolt head 310.

It will be understood that each of the elements described above, or two or more together, may also find a useful application in other types of composite panel arrangements differing from the types described above.

Without further analysis, the foregoing will so fully reveal the gist of the present invention that others can by applying current knowledge readily adapt it for various applications without omitting features that, from the standpoint of prior art, fairly constitute essential characteristics of the generic or specific aspects of this invention and, therefore, such adaptations should and are intended to be comprehended within the meaning and range of equivalence of the following claims.

What is claimed as new and desired to be protected by Letters Patent is set forth in the appended claims.

1. A composite panel structure, comprising a latticelike frame including a plurality of frame elements having meeting corner portions; a plurality of polygonal panels adjacent to one side of said frame and having corner portions overlying the corner portions of adjacent frame elements, the corner portions of said panels being provided with recesses extending substantially diagonally inwardly from the respective corner portions and each having a wider portion and a narrower portion disposed between the respective wider portion and said one side of the frame; and coupling means separably securing said panels to said frame, including substantially annular elastic retaining members mounted at the meeting corner portions of said frame elements and received in the wider portions of the adjacent recesses, said panels being separable from the frame in response to deformation of said retaining members during passage through the narrower portions of the respective recesses.

2. A composite panel structure as defined in claim 1, wherein said recesses are S-shaped in cross section.

3. A composite panel structure as defined in claim 1, wherein each said coupling means further includes guide means mounted between each of said elastic retaining members and the meeting corner portions of said frame, said guide means having four sidewalls that respectively engage along their lengths the narrow portion of a respective one of said recesses.

4. A composite panel structure as defined in claim 3, wherein said retaining members and said guide means are connected together.

5. A composite panel structure as defined in claim 4, wherein each said retaining member comprises a dish-shaped body consisting of spring steel.

6. A composite panel structure as defined in claim 4, wherein each said retaining member comprises a solid, resilient, externally dish-shaped, body.

7. A composite panel structure as defined in claim 4, wherein said retaining members are annular springs, and said guide means has a continuous peripheral groove in said sidewalls thereof to hold a respective one of said annular springs.

8. A composite panel structure as defined in claim 7, wherein each of said annular springs defines in cross section a single round body.

9. A composite panel structure as defined in claim 3, wherein each of said recesses defines a bottom, said frame defines a plane, said guide means and the meeting corner portions of said frame elements define substantially coincidental axes that are substantially perpendicular to said plane, and four corner portions are defined by the four sidewalls of said guide means; and at each said guide means corner portion a projection extending substantially parallel to said coincidental axes and towards said recess bottom; and wherein said retaining members are cup-shaped and each defines a bottom portion defined by said four projections, and each of said retaining members further defines an annular elastic wall that projects from between said projections and into said wider portions of the adjacent said recesses.

10. A composite panel structure as defined in claim 9,

wherein said elastic wall has at least one slot parallel to said coincidental axes.

11. A composite panel structure as defined in claim 10, wherein said elastic wall has four said slots spaced 90° apart.

12. A composite panel structure as defined in claim 11, wherein each said guide means has a centering pin substantially coaxial with said coincidental axes and extending towards said recess bottom, and a hole in said bottom portion of each said retaining member engaged by a respective said centering pin.

13. A composite panel structure as defined in claim 12, including an individual elastic locking means engaging each said centering pin to hold a respective one of said retaining members in place.

14. A composite panel structure as defined in claim 12, wherein said retaining members consist of metal, and said bottom portion thereof incorporates locking means that cooperate with a respective said centering pin to hold the corresponding one of said retaining members in place.

15. A composite panel structure as defined in claim 9, wherein the elastic wall of said retaining members has projections that extend from between said guide means projections and releasably lock with said recesses.
